VAPOR STEAM-HEATING SYSTEM.

1,360,519.

Specification of Letters Patent. Patented Nov. 30, 1920.

Application filed November 3, 1917. Serial No. 200,207.

To all whom it may concern:

Be it known that I, EDWARD E. GOLD, a citizen of the United States of America, residing in the borough of Manhattan, city, county, and State of New York, have invented certain new and useful Improvements in Vapor Steam-Heating Systems, of which the following is a specification.

This invention relates to steam-inlet valves of the kind known as "vapor valves," being adapted to control the admission of steam to radiators by what is known as the "vapor system" or "atmospheric pressure system" of steam heating. Such systems are principally used for the heating of railway cars.

A vapor valve as commonly constructed is closed by the expansion of a thermostat, which receives heat from the spent steam or vapor discharged from the radiators either by being directly exposed to such outflowing vapor, or by being indirectly exposed to the heat therefrom. The result of this construction is that the inlet valve is kept very slightly open, so as to admit a restricted flow of steam to the radiators sufficient to supply the condensation therein and to maintain a slight outflow of vapor to the drip pipe sufficient to keep the thermostat heated and expanded.

This result is accomplished irrespective of the temperature within the car, and when the car becomes overheated it is necessary for the operator to shut off the steam by closing a hand-operated valve. It has been proposed to introduce thermostatic control of the admission of steam by mounting a thermostat within the car and utilizing this thermostat to control a steam-inlet valve, whereby, when the car becomes overheated, to shut off the steam.

The present invention provides an improved construction of vapor valve having electromagnetic means for closing the valve whenever the car becomes overheated. For this purpose the valve is provided, in addition to the ordinary thermostat heated by the outflowing vapor, with an electromagnet which when energized acts to close the valve, and which is in circuit with a circuit-controlling thermostat located within the car.

The system provided by my invention has the advantage over the ordinary vapor valve that when the car becomes heated to the

maximum temperature desired, the electromagnet acts automatically, under control of the car thermostat, to shut off the steam, and holds it off until the car is cooled to a predetermined degree. It has the advantage over such electromagnetically-controlled steam valves as have heretofore been proposed, that waste of steam is prevented by the automatic action of the thermostat, which, as soon as the discharge from the radiators reaches it and heats it enough to expand it, at once throttles the inflow of steam, whereas with an inlet valve controlled only from a car thermostat, the steam would blow freely through until the car was warmed to the normal temperature sufficient to operate the thermostat within the car.

Figure 1 of the accompanying drawings is a fragmentary cross-section of a car showing the improved valve provided by my present invention, in elevation, with its connecting pipes;

Fig. 2 is a vertical longitudinal section of the valve on a larger scale;

Fig. 3 is a transverse section on the line 3—3 in Fig. 2;

Fig. 4 is a transverse section on the line 4—4 in Fig. 2.

Referring first to Fig. 1, A designates the side wall of the car, and B the bottom or floor. C is the train-pipe from which leads a branch pipe *a* which rises into the car. D is, as a whole, the improved valve. It comprises a steam-inlet valve E, a thermostat or diaphragm vessel F, an intervening valve rod or stem, preferably made in two sections, G G', and an electromagnet H, all inclosed in a casing I. The radiator connections and piping are of any usual arrangement. That shown comprises a pipe *b* leading from the valve E to the radiating pipes *c c* which are extended in any usual manner along the side wall of the car. These pipes drain to a low point located usually near the middle of the car, whence a discharge pipe *d* leads to the discharge inlet *e* of the shell I. This shell has on its underside a boss *f* through which connection is made to the drip pipe *g* which passes down through the car floor and affords a free discharge through its open bottom end for the outflowing vapor. It is commonly made flaring or trumpet shape, and is best divided by a partition *h* which, when the car is in motion, diverts air from

85

105

110

beneath the car and causes it to flow up the drip pipe *g* on one side of the partition and flow down the opposite side thereof, so that the air thus circulated contributes to the 5 cooling of the thermostat *F* and causes this to contract more rapidly than it otherwise would.

In the construction shown, the thermostat *F* is not directly exposed to the outflowing 10 vapor, but, by reason of an interposed partition *i*, a chamber *j* is formed through which the vapor may flow, and a chamber *k* is provided in which the thermostat is housed and which is thus cut off from the vapor or steam, 15 and, being open at its top and covered by a removable lid *l*, is accessible by opening this lid to examine the thermostat *F* or replace it when worn out or injured. The thermostat is formed as an expansion vessel or vessels 20 containing a volatile liquid and confined between disks *m m* supported on pins *n n* which are held in notches, so that the thermostat as a whole may be readily lifted out for inspection or replacement. This construction is set forth in my pending application 25 filed September 6, 1917, Serial No. 190,078. For ventilating the chamber *k* in order to cool the thermostat, air-inlet openings *p* are formed in the bottom of the casing and air-outlet openings *q q* are formed 30 in the lid *l*.

The electromagnet *H* is arranged to inclose the valve stem, being thus of the solenoid type of magnet. It comprises a coil *J*, 35 a movable core *K* fastened on the valve stem *G'*, and a stationary core *L* through which the valve stem *G'* freely slides. A spring *M* is provided for pressing the core *K* away from the core *L*. This spring thus serves 40 to open the valve *E* and to exert a tension tending to collapse the thermostat *F* as it cools. In the particular construction shown, the valve stem *G'* is of smaller diameter where it passes through the cores *K L*, and 45 is of larger diameter beyond, where it passes through a wall *r* of the casing which separates the thermostat chamber *k* from the magnet chamber. This enlarged end of the stem is notched to receive the thermostat pin 50 *n*, and to keep this notch on the upper side a pin or key *s* enters the notch, so that the stem is prevented from turning. The stem has a flange *t* which may be cupped, as shown, and which receives the end of the 55 core *K* and forms a shoulder for receiving the thrust of the spring *M*. The reaction of this spring is received against a stationary tube *u* which forms an extension of the core *L*. These details of construction are 60 not important and may be greatly modified. The ends of the wire of the coil *J* pass out through insulating bushings *v v'*, the wire *w* being carried out through a conduit or protecting tube *P* which extends up into the 65 car, so that the wires are led to the thermo-

stat or temperature-controlled circuit closer which is located at any suitable point within the car so as to be exposed to the car temperature.

The thermostatic circuit closer *Q* may be 70 of any suitable construction, for example that set forth in Patent No. 1,214,323, granted January 30, 1917. Its function is to open or close an electric circuit, according as the temperature in the car falls below 75 or rises above the predetermined range of temperatures. When this device closes the circuit the current traverses the coil *J* and the electro-magnet *H* is energized, the cores *K L* are drawn together, and the movement 80 is transmitted through the valve stem to close the inlet valve or tappet *R* constituting the valve member of the steam-inlet valve *E*.

The connecting wires between the magnet terminals *v v'* and protecting conduit *P* 85 are inclosed in a chamber *S* which serves as a junction box. This chamber is best constructed in the manner shown with a tubular central portion *x* inclosing the valve stem, and with a chamber *S* encircling this 90 central portion annularly, as shown in Fig. 3. The chamber *S* is formed of a lower shell *S'* and an upper shell *S²* seated on the casing *I* and fastened thereto by screws *y* or otherwise, so that by removing these screws 95 the upper half *S²* may be easily lifted off to get access to the wires and to the valve stem *G*. The fixed core *L* is, in the construction shown, formed integrally with a disk *L'* which has holes through which the terminals 100 *v v'* pass, and which is rigidly confined in a groove *z* in the casing *I*.

In order to make the magnet *H* accessible for inspection, repair or replacement, the casing *I* is made in two sections, its lower 105 half being immovable, and its upper half *I'* (Fig. 4) being separable, so that by withdrawing fastening screws *a'* it may be lifted off. To disassemble the structure the thermostat *F* is first lifted out, the casing cap *I'* 110 taken off, and the magnet *H* with its cores *K* and *L* and the section *G'* of the valve stem are lifted out together. To enable the stem *G'* to be separated from the stem *G*, they are united by an open joint with or 115 without a cotter pin *b'* (Fig. 3), which, if used, must first be removed. The joint between the two valve stems is a socket joint adapted to lock them together against longitudinal thrusts while permitting lifting off 120 of the stem *G'* from the stem *G*.

In operation, when the steam is first turned on to a cold car, the valve *E* being 125 open, the steam rushes through the radiating pipes, and on blowing out at the discharge end quickly heats up the partition *i*, chamber *k* and thermostat *F*, and the latter expands so as to close the inlet valve wholly or nearly, thereby preventing waste of steam. Thereafter the thermostat keeps the 130

valve barely open, just enough to maintain the circulation of vapor through the radiators. As soon as the car is heated to the maximum for which the thermostat Q is set, 5 this closes the circuit to the magnet H , which acts to close the inlet valve until the temperature in the car falls sufficiently so that the thermostat Q breaks the circuit, whereupon the spring K opens the inlet 10 valve and reestablishes control by the thermostat F . This dual control of the inlet valve by the thermostat Q within the car and the thermostat F exposed to the heat of the discharge from the radiators, results 15 in the maintenance of equable heat in the car and prevents overheating.

As it is sometimes desirable to be able to manually shut off the heating apparatus, a hand-operated shut-off valve T is preferably 20 provided at some convenient point in the pipe b . Commonly the improved construction of valve D , the hand-valve T , and the pipes a b d will be placed beneath one of the transverse seats U of the car, as shown 25 in Fig. 1.

The invention is not limited to the detailed construction shown, which may be widely departed from, or varied according 30 to the requirements of any particular installation. The invention is not limited necessarily to use with the so-called vapor system of car heating, as it is applicable generally to low-pressure heating systems. While designed primarily for the heating of 35 railway cars, it may also be found available in other locations.

Fig. 1^a shows diagrammatically a suitable construction of thermo-electric circuit closer Q . A thermostatic diaphragm vessel 6 reacting against an adjusting screw 7 , expands against a spring plate 8 , the free 40 end of which is movable between adjusting screws 9 , 10 , so that when the maximum temperature is reached it contacts with screw 10 and closes the circuit from wire 11 through 8 , 10 to wire 12 . Suitable connection is made at some convenient point in the 45 circuit with a battery or other source of electric energy, preferably the lighting circuit of the car.

What I claim is:—

1. A heating system comprising a steam-inlet valve, a radiator, a thermostat exposed to the heat of the discharge from the radiator and directly connected to said valve to close it when expanded, an electro-magnet connected to operate said valve, a thermostatic circuit breaker exposed in the apartment to be heated, and a circuit connecting 55 said circuit breaker to said magnet, whereby said valve is normally controlled thermally by the heat of the discharge, and is closed by the magnet whenever the apartment is heated to a prescribed maximum.
- 60 2. In the system of claim 1, the valve

having a valve stem, and the thermostat and electro-magnet both engaging said stem.

3. In the system of claim 1, a separable connection between the electro-magnet and valve adapted to permit the removal and 70 replacement of the magnet.

4. In the system of claim 1, separable connections for the thermostat and the electro-magnet adapted to permit either to be removed and replaced without affecting the 75 valve.

5. In the system of claim 2, the electro-magnet arranged to inclose the valve stem, and the thermostat to act against the end of 80 said stem.

6. In the system of claim 1, a casing for said valve inclosing the magnet and thermostat, and having a discharge inlet and outlet adapted to admit the hot fluid from the 85 radiator into proximity with the thermostat.

7. A thermo-electromagnetic vapor valve comprising a casing, a steam-inlet valve therein, a stem for said valve, an electro-magnet and a thermostat inclosed in said casing, and each in operative engagement 90 with said stem, and said casing having an inlet for admitting hot fluid from a radiator into proximity with the thermostat.

8. A valve according to claim 7, with the casing made with removable portions to 95 give access to the magnet and thermostat.

9. A valve according to claim 7, with the magnet and thermostat mounted to be severally removable.

10. A valve according to claim 7, with the 100 valve-stem made in separable sections, the one connected to the valve and the other removable with the magnet.

11. A valve according to claim 7, with the electro-magnet comprising a core attached 105 to the valve-stem, and a coil inclosing said core, and a spring for retracting the core and opening the valve applied between the core and coil.

12. A valve according to claim 7, with the 110 casing having a removable section inclosing the electro-magnet, and the latter comprising a coil and a fixed and movable core therein, the fixed core formed with a disk flange fitting in said casing, and removable 115 upon the removal of said section of casing.

13. A valve according to claim 7, with the casing having a chamber adjacent to the magnet for receiving the magnet terminals and connecting the circuit wires thereto. 120

14. A valve according to claim 7, with the casing having a chamber between the magnet and steam-valve, forming a junction box for making the circuit connections.

15. A valve according to claim 14, with 125 the junction box divided into sections, one of which is removable to allow access to the connections.

16. A heating system comprising a steam-inlet valve, a radiator, a thermostat exposed 130

4

to the heat of the discharge from the radiator and directly connected to said valve to close it when expanded, a second thermostat exposed in the apartment to be heated, and
5 means governed by the second thermostat and connected to said valve for operating it independently of the first-mentioned thermostat, said means including an electric circuit adapted to be opened or closed by
10 said second thermostat in accordance with

temperature changes of the air in the apartment and acting thereby to cause a quick opening or closing of the valve.

17. A heating system according to claim 16, the means governed by the second thermostat being an electro-motive device directly connected to the valve. 15

In witness whereof, I have hereunto signed my name.

EDWARD E. GOLD.
